BASIL L. SPURR AND FRANK A. TITTEMORE, OF RICHMOND, CALIFORNIA.

REFILLABLE FUSE.

1,257,418.

Specification of Letters Patent. Patented Feb. 26, 1918.

Application filed April 27, 1916. Serial No. 94,000.

To all whom it may concern:

Be it known that we, BASIL L. SPURR and FRANK A. TITTEMORE, citizens of the United States, residing at Richmond, in the county 5 of Contra Costa and State of California, have invented certain new and useful Improvements in Refillable Fuses, of which the following is a specification.

The present invention relates to electric 10 fuses of the inclosed or cartridge type, and more particularly to a fuse cartridge, the fusible element of which can be readily removed and replaced.

Refillable fuse cartridges, as heretofore 15 constructed, have been open to a serious objection; namely that the fusible element may be replaced with one of greater capacity than the original, without such substitution being apparent, since only the outside, or 20 permanent portions of the cartridge, are marked with the rated capacity of the fuse. Thus, by the substitution of a fusible element of greater capacity than that for which the shell is rated, the laws and regulations 25 prescribing the capacity of fuses in relation to the equipment which they are intended to protect may be set at naught, either through ignorance or malicious intention, with very little probability of detection.

30 By the present invention, however, this objection is overcome, since a fusible element of the rated and proper capacity only can be installed within a given cartridge.

The object of the present invention, there- 35 fore, is to provide a fuse cartridge whose fusible element can be quickly and cheaply replaced, and in which a fusible element of the proper capacity only may be installed.

In order to comprehend the invention, 40 reference should be had to the accompanying drawings, wherein—

Figure 1 is a longitudinal section through the center of the fuse.

Fig. 2 is a transverse section taken in the 45 direction of the arrows on the line 2—2 of Fig. 1.

Fig. 3 is a transverse section taken in the direction of the arrows on the line 3—3 of Fig. 1.

50 Fig. 4 is a transverse section taken in the direction of the arrows on the line 4—4 of Fig. 1.

Fig. 5 is a transverse section taken in the direction of the arrows on the line 5—5 of Fig. 1.

In the drawings, the reference numeral 1 designates an insulating shell, formed preferably of compressed fiber or other similar material, and provided with a refractory lining 2, preferably of asbestos. The ends 55 of the shell 1 are exteriorly threaded, as shown at 3 and 4, and a pair of longitudinal sockets 5 and 6 are formed between the shell 1 and the lining 2, extending inwardly from each end. Reinforcing collars 7 and 8, preferably metal, are placed between the shell 60 and the lining, and are formed with grooves in their sides, as shown particularly in Fig. 5, to partially embrace said sockets 5 and 6.

At one end of the fuse is a contact mem- 70 ber 9, herein shown as having a flat exterior blade, although it is to be understood that any form of exterior contacting and supporting member may be employed. The inner portion of the contact blade 9 is formed 75 with a pair of spaced parallel prongs 10, adapted to lie within the sockets 5 of the shell, to prevent said contact member from turning.

The contact member 9 is retained in position by means of lugs 11 projecting from the edges thereof, said lugs lying under a slotted plate or cap 12 which forms a closure for the end of the shell 1 and which is held in position by a screw collar 13.

It is not our intention, however, to limit the form of said contact member to that shown in the drawings, for the contact mem- 85 ber 9 and the cap 13 may, if desired, be formed integrally.

Carried by the contact member 9, between the prongs 10, is an extension 14, to which is permanently attached, as by a rivet or solder, a fusible element 15, here shown as 90 a flat metallic strip.

At the other end of the shell 1 is a sec- 95 ond contact member 16, having inwardly projecting prongs 17 adapted to lie within the sockets 6, said contact member 16 being held in position by lugs 18, an end closing cap 19, and a screw collar 20, in a manner similar to that described above in reference to the contact member 9. Said second contact member 16 carries, between the prongs 100

17, a projecting lug 21, preferably hemispherical in form, as shown in Fig. 1. The end closing caps 12 and 19 are preferably formed with ventilating apertures 12' and 19', to allow a free circulation of air through the shell 1 and around the fusible element 15 to minimize overheating of the same under normal conditions.

A plate 22, preferably dished, as illustrated, lies transversely across the end of the lining 2 within the reinforcing collar 8. This plate is formed with an aperture 23, corresponding very closely in shape and size to the cross section of the end portion 15 of the fusible strip 15. Said end portion of the fusible strip is preferably split, as at 24, and the two parts thus formed are bent over, as at 25, after being passed through the aperture 23 in the plate 22, as shown in Fig. 3, so that the end of the fusible strip is thus securely supported by the plate 22. The projecting lug 21 of the contact member 16 makes electrical contact with the bent over ends 25 of the fusible strip 15 when said contact member 16 is forced down upon the end of the shell 1 by the screw collar 20.

Thus it will readily be seen that in order to remove the fusible element 15, it is only necessary to unscrew the end collars 13 and 20, and release the ends 25 of the fusible strip from their bent-over engagement with the apertured plate 22. The contact member 9 with the fusible element 15 may then be withdrawn, and a new contact member and fusible element inserted in its place. If the fuse be melted, as would usually be the case, one portion thereof comes out with the contact member 9, and the other portion 40 may be readily withdrawn from the other end of the shell by removing the plate 22 and the portion of fuse connected therewith.

The contact member 9 being permanently attached to the fusible element 15, the capacity of said fusible element can be stamped or otherwise marked exteriorly upon said contact member; and by providing a contact member of a different size or shape for each size of fusible element, only 50 a fusible element of the proper capacity can be inserted in a given shell. Moreover, the fusible element must pass through the aperture 23 in the plate 22, so that with a given plate, the size of the fuse is positively 55 limited by the size of the aperture in said plate; and by correlating the exterior diameter of the plate 22 with the size of the aperture 23 therein, an additional and effectual check is provided against the possibility 60 of the use of a fusible element of greater capacity than that for which the shell is designed.

We are aware that our device may be embodied in other forms, without in any way 65 affecting the essential principles of invention

involved therein, and we therefore do not wish to be construed as limiting ourselves in this regard, but on the contrary, we wish to be construed as claiming the invention as broadly as the state of the art will permit.

Having thus described our invention, what we claim as new and desire to protect by Letters Patent is:—

1. An inclosed electric fuse comprising a substantially cylindrical insulating shell 75 having a longitudinal socket formed in its wall and extending inwardly from its end; a contact member removably associated with the end of said shell; an extension carried by said contact member and adapted to lie 80 within said socket to prevent the rotation of said contact member; a second contact member associated with the other end of said shell; and a fusible metallic element within said shell, each end of said fusible 85 element having electrical connection with one of said contact members.

2. An inclosed electric fuse comprising a substantially cylindrical insulating shell having an exteriorly threaded portion at 90 each end; a contact member adapted to form a closure for one end of said shell; a screw collar for holding said contact member in position; a fusible metallic element having one end attached to said contact member 95 and projecting inwardly therefrom; a plate transversely disposed within said shell, said plate having an aperture for receiving and holding the free end of said fusible element; a second contact member forming a closure 100 for the other end of said shell and having electrical connection with the end of said fusible element held by said plate; and a second screw collar for holding said second contact member in position.

3. An inclosed electric fuse comprising a substantially cylindrical insulating shell having an exteriorly threaded portion at each end; a pair of contact members forming closures for the ends of said shell; screw 110 collars for holding said contact members in position; means for preventing the rotation of said contact members with respect to said shell; an apertured plate transversely disposed within said shell near one end thereof; 115 and a fusible metallic element, one end thereof being permanently attached to one of said contact members and the other end passing through the aperture in said plate and being removably attached thereto and 120 having electrical connection with the other of said contact members.

4. An inclosed electrical fuse comprising an insulating shell, a contact member for fitting over one end thereof, a fusible metallic element having one end permanently attached to said contact member and projecting inwardly therefrom, a plate transversely disposed within said shell, said plate having an aperture for receiving and holding

the free end of said fusible element, a second contact member for fitting over the other end of said shell and having electrical connection with the end of said fusible element held by said plate, and means for holding said contact members in position over the ends of said shell.

In testimony whereof we have signed our names to this specification in the presence of a subscribing witness.

BASIL L. SPURR.

FRANK A. TITTEMORE.
